DOUBLE ACTING OVERSHOT APPARATUS

Franklin L. Le Bus, Sr., Longview, Tex.

Application July 15, 1954, Serial No. 443,597

9 Claims. (Cl. 294—102)

This invention relates to improvements in fishing tools for oil wells and more particularly, but not by way of limitation, to improvements in a clutch type of releasing overshot adaptable for recovering lost drill pipe, drill collars, and the like, from an oil well bore.

Numerous fishing apparatus, and particularly mechanically released overshots of various type has been used throughout the oil industry for recovering broken off parts of drill pipe, sucker rods, drill collars, casing or tubing that are dropped in the well bore, which in most instances must be recovered before the drilling operation can proceed. In many drilling operations the broken off portion of the lost drill pipe severs, or parts in more than one place, for example, it may sever both in the drill pipe, and in the drill collars which are usually of a larger size than the pipe. Consequently the operator cannot be sure which of two or more sizes of overshot apparatus is necessary in order to engage a broken off portion. Furthermore, broken off portions of pipe in falling in the well may become stuck in the well bore and cannot be readily pulled up and removed therefrom by gripping the pipe with a fishing tool at only one place of contact.

The present invention is generally concerned with an improvement in a clutch type releasing overshot for the removal of lost drill pipe, drill collars, casing or tubing where the overshot may be set to engage the lost member at two different vertically spaced positions on broken off pipe of the same size, or of variable sizes, and where one engagement may be independent of the other to engage the pipe in one action, whereby valuable operating rig time is saved by eliminating a re-running of fishing tools for variable sizes of broken off members.

It is an important object of this invention to provide an overshot fishing tool for engaging lost fish in a drilled well bore which may engage the fish at two different points of contact in order to remove the fish from the bore.

And still another object of this invention is to provide an overshot fishing tool for the removal of lost fish in a well bore which operates to engage broken off pipe having variable sizes of diameters, and at two different vertically spaced positions, and where one position of engagement may be independent of the other.

And still another object of this invention is to provide an overshot for recovering lost fish of variable sizes adapted to engage the fish at two different places in one action and which will release at both points of contact simultaneously.

And still another object of this invention is to provide an overshot fishing tool for recovering lost fish in well bores adapted to engage fish of variable sizes at different points of contact and which efficiently packs off the engaging members and also provides for milling off rough edges of the top of the fish preventing injury to the packer.

And still another object of this invention is to provide an overshot fishing tool contacting lost fish at two different positions of engagement which is simple and efficient in operation, and particularly provides for simul-

2

taneous engagement and release of the slip members with the fish at the two different spaced points of contact.

Other objects and advantages of the invention will be evident from the following detailed description, read in conjunction with the accompanying drawings, which illustrate my invention.

In the drawings:

Figure 1 is a sectional elevational view with certain parts in elevation of the upper portion of the overshot apparatus.

Figure 1A is a continuation of Fig. 1 showing the lowermost portion of the overshot apparatus.

Figure 2 is an enlarged detail view in perspective of the clutch mechanism.

Figure 3 is a broken sectional elevational view similar to Fig. 1 showing a fish of variable diameters disposed therein.

Figure 4 is a view similar to Fig. 3 showing a slightly different disposition of the fish relative to the overshot apparatus.

Figure 5 is a sectional elevational view of a modification of the apparatus.

Referring to the drawings in detail, reference character 1 designates an upper head member of the double acting

overshot apparatus indicated generally by the reference character 10. The head 1 has a threaded tapered portion 2 to engage with an overshot pipe or fishing pipe of a drill stem (not shown). The head 1 is provided with an elongated bore 3 and is connected at 4 with an upper cylindrical housing or bowl 5 which in turn is connected by complementary threads 6 to a lower cylindrical housing or bowl member 7 (Figs. 1 and 1A). The housing member 7 is connected at its lowermost portion by complementary threads 8 with a guide member 9 having a cam portion 11 to guide a "fish," such as broken off pipe or the like, into the overshot apparatus in the usual manner. A cylindrical control mandrel or sleeve 12 is disposed in the overshot housings 5 and 7, with the upper section 12 connecting with the lower control cylinder 13 through complementary threads 14 (Fig. 1A).

The bore 3 of the upper head 1 is provided with a countersunk, or grooved portion 15 having diametrically opposed and inwardly directed lugs 16, the lower end of which is flush with the lower end of the head 1 as at 17.

45 A circular anti-friction apertured bearing member 18 is interposed between the upper head 1 and top 19 of the upper control sleeve 12 (Fig. 1). A helical control spring 20 is disposed around the upper sleeve 12 and is anchored at its lower end on shoulders 21 of the control sleeve 12

50 and its opposite upper end against the lower face of the anti-friction bearing 18. The control sleeve 12 is provided with a central bore 24 communicating with bore 3 and has a recessed portion 25 in its upper end providing shoulders 26 for supporting a cylindrical mill 27 provided with mill

55 teeth 28 for a purpose as will be hereinafter set forth. The mill 27 is held against the shoulder 26 by diametrically opposed studs 29 extending through aligned apertures 30 in the sleeve 12 in any suitable manner.

A plurality of spaced segmental slip members 32 are disposed around the control sleeve 12 and are held thereon by a spring retainer ring 33. A helical spring

60 34 is anchored between the circumferential shoulder 21 and the slips 32. The spring 34 encircles the upper sleeve 12 and is held thereon by a retainer sleeve 35 having outwardly extending shoulders 36 for anchoring the bottom of the spring 34. It will be apparent that the spring 34 is of less thickness and lighter weight than the main spring 20 and consequently has less intensity in its application of tension or compression. Furthermore, the

65 70 spring 34 is permitted to move vertically along the sleeve 12 permitting vertical movement of the slips 32 vertically upward along the outer periphery of the sleeve 12 for a

purpose as will be hereinafter set forth. The sleeve 12 may be a cage-like structure through a plurality of circumferentially spaced apertures 31 disposed substantially adjacent the slip members 32, if desired. The upper bowl member 5 is provided with an inwardly directed tapered portion 32^a for cooperation with the slips 32 in a manner as will be hereinafter set forth.

At a point below the slips 32, the upper control sleeve 12 is provided with a pair of diametrically opposed vertically disposed slot portions 37 and 38 (Figs. 1A and 2) communicating with a pair of horizontally disposed recesses, or slot portions 39 and 40, respectively. It will be apparent from Fig. 2 that there are two diametrically opposite vertical slots connecting and communicating with the horizontal recesses or slots 39 and 40. The upper housing bowl 5 is provided with a pair of inwardly directed diametrically opposed lugs 42 and 43 cooperating with both the vertical and horizontal slots in a manner as will be hereinafter set forth.

The upper control sleeve 12 is engaged with the lower control sleeve 13 by the complementary threads 14, assisted by suitable set screws 45 arranged at diametrically opposed positions therebetween (Fig. 1A). The outer periphery of the lower control sleeve 13 is provided with a circular recessed portion 46 in which is disposed an O-ring sealing member 47 preventing leakage of water, mud and other debris between the walls of the upper and lower sleeves 12 and 13, respectively. The lower control sleeve 13 has a reduced cut away portion providing shoulders 48 for anchoring the upper end of a helical spring 50 surrounding the lower control sleeve 13 in a manner similar to the upper spring 34. The spring 50 is retained around the sleeve 13 by a sleeve retaining ring 51 having an outwardly directed circular flange 52 upon which the bottom end of the spring 50 is anchored. Below the circular flange 52, a second set of circumferentially spaced segmental slip members 54 surround the sleeve 13 and are held thereagainst by a spring retaining ring 55 in the usual manner. In similar manner, the slips 54 are permitted vertical movement with movement of the floating retainer ring 51 and the spring 50 as will be hereinafter set forth.

The lower portion of the control sleeve 13 is provided with a mill member 56 having mill teeth 57 similar to the mill 27 in the upper part of the overshot apparatus. The lower body member 7 is provided with an inwardly directed taper 54^a cooperating with the set of slips 54 in a manner as will be hereinafter set forth. Furthermore, the body 7 is cut away at 58 providing an undercut shouldered portion against which is anchored a rubber packing ring 59 anchored therein by a steel retaining ring 60. The rubber sealing ring 59 prevents leakage of mud, water and other debris between the lower body 10 and the lost fish upon disposition of the fish within the overshot apparatus. The top of the overshot guide 9 by engagement with the bowl 7 through complementary threads 8 supports the retaining ring 60 at 61 (Fig. 1A). A packer ring 63 is provided against the lower end of the upper sleeve 12 (Fig. 1A) and held therein by a retainer ring 64 in turn secured to the lower sleeve 13 by diametrically opposed set screws 65 extending through apertures 66 in any suitable manner.

Operation

In operation, a "fish," such as broken off drill pipe, tool joints, drill collars and the like, in the well bore is brought into contact with the overshot fishing apparatus by lowering the overshot apparatus 10 on the usual fishing string or wash pipe (not shown) so that the mill guide 11 will direct the broken off fish into the apparatus 10 in the usual manner. As is clearly shown in Fig. 3, the fish or severed pipe 68 has a jagged top portion 69, and may consist of a portion of the drill pipe usually of smaller diameter 70 connecting with the drill collars 71 of larger diameter. In such a situation, it would be difficult

to predetermine the size of the overshot apparatus for recovery of the fish, and thus may necessitate more than one trip into the well bore to properly engage the lost fish. As shown in Fig. 3, the overshot apparatus 10 is lowered over the fish until the top 69 of the smaller sized pipe 70 engages with the mill teeth 28, thereby anchoring the fish 68 in the overshot 10 whereby the main control spring 20 exerts a downward thrust on the control sleeves 12 and 13 to preclude any vertical movement of the sleeves 12 and 13 during downward movement of the housing 5 and 7.

It will thus be seen that the outer housings 5 and 7 of the overshot apparatus 10 move downwardly over the fish 68 with the lugs 42 and 43 slidably in the opposed longitudinal slots 37 and 38 respectively. The downward movement of the outer housing members 5 and 7 relative to the control sleeves 12 and 13 permits tapers 32^a and 54^a to move away from their cooperating sets of slips 32 and 54 respectively so that the slips may be placed in a non-engaging or released position. In this position, the lugs 42 and 43 are disposed adjacent the lowermost portion of the slots 37 and 38 and in alignment with the horizontal recesses 39 and 40. When it is desired to engage the overshot with the fish, it is only necessary to move the outer housings 5 and 7 upwardly causing the tapers 32^a and 54^a to contact the sets of slips 32 and 54, respectively, thereby moving the slips inwardly into simultaneous engagement against the fish at two vertical points of contact. The separate slip springs 34 and 50 permit independent operation of the sets of slips 32 and 54 respectively when engaging the lost drill pipe or the like. The tension of the helical slip springs 34 and 50 will assist the tapered housing portions in engagement of the slips.

As noted in Fig. 3, it will be apparent that the upper set of slips 32 will contact the pipe 70 of smaller size, while the lower slips may contact a tool joint, pipe collar or the like of larger diameter as illustrated at 71, and in a lowermost position therefrom. In Figs. 1 and 1A the size of the slips 32 for engaging a smaller diameter pipe is less than the size of the slips 54 for engaging tool joints, drill collars and the like, usually of larger diameter. Although not limited thereto, the smaller slips are generally sized to engage pipe approximately four and one-half inches I. D., while the slips 54 are sized to engage drill collars of a diameter of approximately five and three-quarter inches I. D. It will thus be seen that the double acting fishing tool may be utilized for making independent contact with pipe at two different places and of variable sizes. However, it may also be used for contacting pipe of the same size at two places by merely substituting the smaller sized slips at the lower end of the mandrel for the slips 54. The slip springs 34 and 50 provide for the independent action of the separate sets of slips 32 and 54 during a setting of the overshot. The anchoring space of the springs 34 and 50 and the floating slip rings 35 and 51 permits for a longer travel of the slips during a lowering of the overshot over a fish to compensate for any variance in distance between the separate bit of the spaced sets of slips 32 and 54. It has been found that in the double acting overshot, a worm tool joint may prevent proper engagement of the lower slips 54, however, the independent action of the separate sets of slips would set the upper slips 32, thereby providing a biting contact with the fish.

In the event an engaged fish is stuck and cannot be removed, it may be necessary to release the overshot, and the present invention contemplates a release of both sets of slips 32 and 54 from both points of contact simultaneously. The release of the engaging slips is accomplished by again moving the outer housing 5 and 7 downwardly and placing the lugs 42 and 43 into alignment with the slots 39 and 40, which may be disposed therein by a turn in a right hand direction, thereby holding the control sleeve 12 in an upward position so that the slips

32 and 54 will be maintained in a released position from the fish 68. In this manner, the overshot apparatus 10 may be removed from the well bore so that other apparatus (not shown) may be utilized for releasing the stuck fish.

It will be apparent that it is not necessary that the anchoring point of the lost fish be made against the upper mill teeth 28, particularly if the upper end 69 of the fish is not long enough to be brought into contact therewith. In such a situation, the anchoring of the control sleeves 12 and 13 may be accomplished at a lower point on the fish, such as against the mill teeth 57. In Fig. 4 is shown the overshot apparatus engaged over a fish having a smaller pipe 70 but the anchoring is accomplished by engagement with the mill teeth 57 against the larger sized pipe 71. The operation of the overshot apparatus is exactly the same for an anchoring against the teeth 57 as against the mill 28. Once the fish 68 is anchored, either set of slips 32 and 54 may take hold to remove the fish from the well bore, assuming it is not stuck therein. However, if the fish 68 is stuck, the overshot 10 may be released through movement of the lugs 42 and 43 in the manner above referred to.

It will thus be seen that the present invention contemplates a double engaging, or double acting overshot which will independently engage the lost fish at two different points of contact, and for different sizes of connecting drill pipe. In many instances, the broken off fish and particularly the pipe above a tool joint may be slotted, or broken, and any engagement of a set of slips thereby would cause a cave-in, or mashing of the slotted pipe, so that an efficient engagement cannot be made. However, once the fish is anchored by either set of mill teeth 28 or 57, if one set of slips could not make engagement for some reason, the other set of slips will engage at a different position for retrieving the fish 68 from the bore.

In Fig. 5 is shown a modification of the overshot apparatus 10 for a single engagement of the fish at only one point of contact. The overshot apparatus shown in Fig. 5 comprises substantially the same structure, except that the sectional control sleeves 12 and 13 of the preferred embodiment have not been utilized, and in lieu thereof, a unitary releasing control sleeve 80 is disposed with the connecting housing members 5 and 7. The overshot structure in Fig. 5 has several interchangeable parts with that shown in Figs. 1 to 4, in that the lower housing 7 is the same as that utilized with the preferred embodiment, and connects with the upper head member 1 at the threads 4. However, the housing member 5 of the preferred embodiment has been omitted to provide for the direct assembly of the head 1 and the lower housing 7, and the unitary control sleeve 80 is utilized in lieu of the sectional control sleeves 12 and 13. It will be apparent that the cylindrical unit 80 is provided with a sleeve portion 81 of larger diameter disposed in the bowl member 7. The sleeve 81 is provided with an integral upstanding sleeve portion 82. The upstanding sleeve 82 is of lesser diameter than the sleeve 81.

The main control spring 83 surrounds the control unit 80 and is anchored at its top against the lower face 84 of the upper head 1, and at the bottom on a circumferential flange, or shoulder 85 provided on the outer periphery of the sleeve 81. The circular anti-friction bearing 86 rests on a shoulder 87 provided by the reduced portion between the sleeves 81 and 82 of the unit 80. A mill ring 88 is secured to the inner periphery of the sleeve 81 through set screws 89 in the usual manner. The mill ring 88 is provided with teeth 90, and the lower portion of the sleeve 81 has circumferential teeth 91 for a purpose as will be hereinafter set forth.

Only one set of segmental slips 92 are carried by the sleeve 81 and retained thereon above a shouldered portion 93 by a suitable spring retaining ring 94. It will be apparent that the slips 92 are anchored in a different manner from that in the preferred embodiment in that

they do not have a movable retainer ring such as rings 35 and 51 permitting extended longitudinal movement of the slips. In the single operation shown in the modification, the slips are only permitted vertical movement between the bottom of the flange 85 and the shoulder 93. The outer housing 7 is provided with an inwardly directed tapered portion 92a. Below the slips 92, the housing also includes the sealing ring 59, retaining ring 60 and guide member 9 and cam surface 11 as that of the preferred embodiment.

The operation of the single engaging overshot is substantially the same as that of the double acting structure of the preferred embodiment in that the overshot is lowered over the fish (not shown in this figure) until the upper jagged edge thereof engages the mill teeth 90. The mill teeth 91 will knock off any jagged edges of the upper portion of the fish as it passes thereby and also assists the anchoring operation of the mill teeth 90. The downward thrust of the main spring 83 on the control sleeve 81 maintains it in a substantially rigid, stationary position relative to any fish that may be anchored against the mill teeth 90, thus permitting the overshot bowl 7 to move downwardly so that the tapers 92a will move away from the slips 92 and provide a disengaged, or released position relative to the fish. Movement of the bowl 7 relative to the sleeve 81 is provided by the diametrically opposed longitudinal grooves, or slots 96 provided in the neck, or smaller sleeve portion 82. The grooves 96 communicate with opposed recesses 97 arranged substantially in the same manner as that of the preferred embodiment. The upper head 1 is provided with the diametrically opposed flanges, or lugs 16 which are adapted to engage in the slots 96. As the housing 7 moves downwardly the lugs 16 will be moved downwardly in the slots 96, permitting the taper 92a to move away from and release the slips 92. However, if it is desired to engage the slips with a fish (not shown), the outer bowl 7 is moved vertically upward thereby moving the lugs 16 upwardly with the taper 92a forcing the slips into engagement with a fish.

After engagement with the slips 92, if it is found the fish is stuck, the slips are released by again moving the bowl 7 downwardly, simultaneously moving the lugs 16 downwardly into alignment with the horizontal recesses 97, after which upon a right hand movement of the overshot apparatus will position the lugs 16 in the recesses 97 and thereby hold the central unit 80 in an upward position so that the slips will be in a position of release and the overshot apparatus may be moved from the well bore for any further operation that is desired.

It will be apparent that an operator may use the single acting overshot apparatus as shown in Fig. 5 for one biting engagement at one place on a lost fish. However, if a situation is encountered where the broken off pipe is of variable diameter and two places of engagement are desired, the overshot apparatus set forth in the preferred embodiment can easily be utilized by a simple alteration of the modified single acting unit of Fig. 5. When desired to alter the single unit of Fig. 5, the upper head 1 is unthreaded from the lower housing 7 permitting removal of the control unit comprising sleeves 81 and 82 and slips 92 therefrom. The sectional control sleeves 12 and 13 carrying the double slips 32 and 54, along with the double slip springs 34 and 50 and retaining rings 35 and 51, are substituted by insertion into the lower housing 7. The upper housing 5 is then engaged with the lower housing after which the head 1 is brought into assembled relation therewith. With this change, the double acting overshot apparatus is complete and ready for operation.

From the foregoing, it will be apparent that the present invention contemplates an improved overshot fishing apparatus in that it may be set in two places for pipes or drill collars of different sizes at the same time with one action, and the operating action may be from one of two points of anchoring the broken pipe in the

overshot to permit the functioning of a single control sleeve having a plurality of sets of slips disposed at spaced vertical points in the overshot, and which slips are capable of independent engagement of the pipe at the variable points of contact, but release simultaneously therefrom. Furthermore, the invention contemplates the use of interchangeable parts between a double acting and single acting overshot apparatus by substitution of the control sleeves and necessary adjunct parts thereto from a single operation to a double operation and vice versa, so that the operator is afforded a fishing tool with diversified advantages capable of accomplishing an efficient result in almost any type of fishing operation.

Changes may be made in the combination and arrangement of parts as heretofore set forth in the specification and shown in the drawings, it being understood that any modification in the precise embodiment of the invention may be made within the scope of the following claims without departing from the spirit of the invention.

I claim:

1. In an overshot apparatus for removing broken off pipe and the like from oil well bores comprising a cylindrical housing adapted to be lowered over the pipe, a control sleeve disposed in the housing, a plurality of sets of segmental slips carried by the control sleeve at longitudinally spaced positions thereon, tapering means provided on the housing adjacent each set of slips and cooperating therewith to effect a gripping engagement of the slips with the pipe, cooperating flange and slot means provided on the housing and the control sleeve to permit longitudinal movement between the housing and the control sleeve, and main spring means for anchoring the control sleeve during longitudinal movement of the housing in one direction.

2. In a double acting overshot apparatus for removing broken off pipe and the like from oil well bores comprising a cylindrical housing adapted to be lowered over the pipe, a control sleeve disposed in the housing, a plurality of sets of segmental slips carried by the control sleeve at longitudinally spaced positions thereon, tapering means provided on the housing in proximity of each set of slips and cooperating therewith to effect a gripping engagement of the slips with the pipe, and slip spring means carried by the control sleeve and cooperating with each set of slips to provide independent operation of the slips relative to each other, and cooperating flange and slot means provided on the housing and the control sleeve to permit longitudinal movement between the housing and the control sleeve, and main spring means for anchoring the control sleeve during longitudinal movement of the housing in one direction.

3. In a double acting overshot apparatus for removing broken off pipe and the like from oil well bores comprising a cylindrical housing adapted to be lowered over the pipe, a control sleeve disposed in the housing, a plurality of sets of segmental slips carried by the control sleeve at longitudinally spaced positions thereon for engaging connecting pipe of two different sizes at two different points of contact, tapering means provided on the housing in proximity of each set of slips and cooperating therewith to effect a gripping engagement of the slips with the pipe, said housing adapted for longitudinal slidable movement relative to the control sleeve to alternately move the tapering means toward and away from each set of slips, main spring means for anchoring the control sleeve during sliding movement of the housing in one direction providing a release of the slips, and slip spring means carried by the control sleeve and cooperating with each set of slips to provide independent operation of the slips during engagement with the pipe.

4. In a double acting overshot apparatus for removing broken off pipe and the like from oil well bores comprising a cylindrical housing adapted to be lowered over the pipe, a control sleeve disposed in the housing, a plu-

rality of sets of segmental slips carried by the control sleeve at longitudinally spaced positions thereon for engaging connecting pipe of two different sizes at two different points of contact, tapering means provided on the housing in proximity of each set of slips and cooperating therewith to effect a gripping engagement of the slips with the pipe, said housing adapted for longitudinal slidable movement relative to the control sleeve to alternately move the tapering means toward and away from each set of slips, main spring means for anchoring the control sleeve during sliding movement of the housing in one direction to effect a simultaneous release of the slips, and slip spring means carried by the control sleeve and cooperating with each set of slips to provide independent operation of the slips during movement of the housing in an opposite direction from the first mentioned direction to cause engagement with the pipe.

5. In a double acting overshot apparatus for removing broken off pipe and the like from oil well bores comprising a cylindrical housing adapted to be lowered over the pipe, a control sleeve disposed in the housing, a plurality of sets of segmental slips carried by the control sleeve at longitudinally spaced positions thereon for engaging connecting pipe of two different sizes at two different points of contact, tapering means provided on the housing in proximity of each set of slips and cooperating therewith to effect a gripping engagement of the slips with the pipe, said housing adapted for longitudinal slidable movement relative to the control sleeve to alternately move the tapering means toward and away from each set of slips, main spring means for anchoring the control sleeve during sliding movement of the housing in one direction providing a simultaneous release of the slips, slip spring means carried by the control sleeve for each set of slips, a floating retainer ring anchoring one end of each slip spring means, each slip and ring means cooperating with a respective set of slips to provide independent operation of the separate sets of slips during contact of the tapering means thereagainst to cause engagement with the pipe.

6. In a double acting overshot apparatus for removing broken off pipe and the like from oil well bores comprising a cylindrical housing adapted to be lowered over the pipe, a control sleeve disposed in the housing, a plurality of sets of segmental slips carried by the control sleeve at longitudinally spaced positions thereon for engaging connecting pipe of two different sizes at two different points of contact, tapering means provided on the housing in proximity of each set of slips and cooperating therewith to effect a gripping engagement of the slips with the pipe, said housing adapted for longitudinal slidable movement relative to the control sleeve to alternately move the tapering means toward and away from each set of slips, main spring means for anchoring the control sleeve during sliding movement of the housing in one direction providing a simultaneous release of the slips, slip spring means carried by the control sleeve, a floating retainer ring anchoring one end of the slip spring means, said spring and ring means cooperating with each set of slips to provide independent operation of the separate sets of slips during contact of the tapering means thereagainst to cause engagement with the pipe, and clutch means cooperating between the housing and the control sleeve to permit longitudinal movement therebetween, said clutch means having cooperating slot and flange means permitting rotation of the housing relative to the sleeve in one position of slidable movement therebetween to maintain the slips in released position.

7. In a double acting overshot apparatus for removing broken off pipe and the like from oil well bores comprising a cylindrical housing adapted to be lowered over the pipe, a control sleeve disposed in the housing, slip means carried by the control sleeve and engaging broken off connecting pipe of two different sizes in at least two different points of contact, spring and ring

means cooperating with the slip means to provide independent operation of the slip means at each point of contact, and releasing means cooperating with the slip means to provide for a simultaneous release at both points of contact in one action of the slip means.

8. In an overshoot apparatus for removing broken off pipe and the like from well bores comprising a cylindrical housing to be lowered over the pipe, a unitary control sleeve disposed in the housing, a plurality of segmental slips circumferentially disposed around the control sleeve, tapering means provided on the housing adjacent the slips for alternately effecting engagement and disengagement of the slips with the pipe, a reduced sleeve portion integral with the control sleeve, a pair of diametrically opposed longitudinal slots provided in the reduced sleeve portion, a pair of diametrically opposed flanges carried by the housing and cooperating with the longitudinal slots to permit longitudinal movement between the housing and the sleeve during engagement and disengagement of the slips with the pipe, and horizontal slot means provided on the reduced sleeve and communicating with the longitudinal slots and adapted to receive the flanges therein in one position of the housing through a right hand rotation thereof relative to the control sleeve to maintain the slips in a disengaged position with the pipe.

9. In a fishing tool apparatus for removing broken off pipe and the like from well bores having an outer cylin-

drical sectional housing comprising an upper head member, a lower bowl member and an intermediate bowl member interposed between the head and the lower bowl, a sectional control sleeve disposed in the housing, said control sleeve carrying a plurality of sets of slips disposed at longitudinally spaced positions on the control sleeve for engaging connecting pipe of two different sizes in at least two different points of contact, tapering means provided on the housing for effecting alternate engagement and disengagement of the slips with the pipe, and spring and ring means cooperating with the slips to provide independent operation of each slip relative to each other, said apparatus capable of a single engaging contact with the pipe by substitution of the sectional control sleeve and slips thereon for a unitary control sleeve having only one set of slips thereon, said interchange of control sleeves provided by elimination of the intermediate bowl for direct connection between the upper head and the lower bowl of the cylindrical housing.
